UNITED STATES PATENT OFFICE.

JOSÉ DUCCI, OF SANTIAGO, CHILE.

REGULATOR FOR VICTROLAS.

Application filed April 19, 1923. Serial No. 633,261.

This invention has reference generally to improvements in regulating devices and more particularly relates to a regulator for a victrola.

5 The principal object of the present invention is to provide a regulating device intended for use in localities where there is a variation of current in the main supply circuit the device being adapted for connection with a victrola so that the variation of the current will not effect the operation of the device.

10 The invention comprises briefly the provision of a regulating device employing an electro-magnetic means adapted to be interposed in the main electrical supply circuit and operably connected with a centrifugal governor the latter being in turn connected with the main operating motor and the turn 15 table of the device.

15 A more specific object of the invention is to provide means for adjusting the electro-magnetic mean so that the ratio of speed of the motor and the shaft of the turn table 20 may be altered to suit the required condition.

25 Other objects, as well as the nature, characteristic features and scope of the invention will be more readily apparent from the following description taken in connection with the accompanying drawings and pointed out in the claims forming a part of this specification.

30 The invention is clearly illustrated in the accompanying drawings in which the figure represents a plan looking towards the under side of the turn table support, the electrical circuits being shown diagrammatically.

35 Referring now, more particularly to the accompanying drawings, there is provided a support A beneath the turn table of the device on which is mounted a motor B the latter being interposed in the main electrical supply circuit C and operably connected 40 with a centrifugal governor D as by a belt and pulley arrangement E. An electro-magnetic device generally indicated by the letter F is also interposed in the main electrical supply circuit by conducting wires H 45 and operably connected with the governor D by a braking device I so that when there is a variation in the main supply circuit C the electro-magnetic device will act against the current supply of the main electric circuit and operate the braking device and as

this is connected with the centrifugal governor and receives its motion from the motor B it will be apparent that the governor will transmit a regulating motion to the turn table shaft J through the worm K of 60 the governor shaft.

The details of construction of the braking device and the electro-magnetic device which act on the centrifugal regulator are as follows:—

65 The ends of a yoke 2, rest on disk 1 of the centrifugal regulator provided with small friction sponges, preferably two made of leather or felt. A lever 4 is provided for carrying the yoke at one end while this lever 70 is pivoted medially of its end at the point 5 on a transverse bar which forms part of the supporting box of the mechanism. On the other end of this lever 4 there is a slider which can move alongside of the lever whose 75 definite position is fixed by a screw 7. This slider 6 supports by means of a bolt 8, a cast iron armature 9. Bracket 10 supports, around armature 9 (fixed at the base), a magnetic solenoid 11 in whose interior slides 80 armature 9. Bracket 10 has a groove 12 which enables it to move it, parallel to armature 9, by means of an outside handle 14.

85 This magnetic coil is worked either by direct or alternating current, with a derivation of the circuit, taken by the extremes of the motor thus remaining in a parallel position. The operation is the following:

90 A potential variation in the netting tends to produce a variation in speed in the motor, but at the same time it alters the magnetic tension of armature 9 influencing the pressure that lever 4 exerts on the centrifugal regulator 1 and altering therefore the load of the motor. This result can be perfectly 95 compensated by adjusting the definite position of slider 6.

100 By moving bracket 10 from the outside, parallel to armature 9, owing to the groove 12, the variations of spontaneous speed that sometimes are needed, can be obtained because the strength of the armature 9 changes with this movement. In order that a blow or any other cause may not take armature 9 out of the roll 11, a limiting stop 13, is 105 placed at the left of lever 4.

110 It is believed in view of the foregoing that a further detailed description of the operation of the invention will be entirely unnecessary. Likewise it is believed that 110

the advantages of the invention will be readily apparent. 20

Claims—

1. In combination, a main supply circuit, 5 a motor interposed in the circuit, a speed responsive device, electro-magnetic means in said circuit acting in response to current variations, braking means operated by the electro-magnetic means and acting on the speed responsive device to maintain the speed 10 of the device and the motor constant regardless of current variations in the supply circuit, said electro-magnetic means including a slidably and swingably mounted bracket, 15 a solenoid carried by the bracket, an armature slideable in the solenoid, and a pivotally mounted lever pivotally and adjustably mounted in the armature and operatively connected to the braking means, substantially as and for the purposes set forth. 25
2. In combination, a main supply circuit, a motor interposed in the circuit, a speed responsive device, electro-magnetic means in said circuit acting in response to current variations, means for adjusting the electro-magnetic means including a manually operable screw adjustably and swivelly connected with said electro-magnetic means, and braking means operated by the electro-magnetic means and acting on the speed responsive device to maintain the speed of the motor constant regardless of current variations in the supply circuit. 30

In testimony whereof I affix my signature.

DR. JOSÉ DUCCI.
